UNITED STATES PATENT OFFICE.

CHARLES EDWARD KAYLOR, OF LEQUIRE, OKLAHOMA.

DISPLAY-STAND.

1,401,084.

Specification of Letters Patent. Patented Dec. 20, 1921.

Application filed March 14, 1921. Serial No. 452,360.

To all whom it may concern:

Be it known that I, CHARLES EDWARD KAYLOR, a citizen of the United States, residing at Lequire, in the county of Haskell, 5 in the State of Oklahoma, have invented certain new and useful Improvements in a Display-Stand, of which the following is a specification.

This invention relates to improvements in racks or stands for holding articles in convenient and accessible position, more particularly duplicate articles, such as bolts, screws and the like of varying sizes, and has for one of its objects to provide a simply 10 constructed device whereby the different articles may be brought into convenient and accessible position without the necessity of the person requiring the article to move from his position.

20 Another object of this invention is to so produce a device of this character so constructed that a broken or impaired part may be removed without discarding the remainder of the apparatus.

25 With these and other objects in view the invention consists of such novel features of construction as hereinafter shown and described and then specifically pointed out in the claim, and in the drawings illustrative 30 of the preferred embodiment of the invention.

Figure 1 is a side elevation of the improved device.

Fig. 2 is a plan view.

35 Fig. 3 is an enlarged transverse section on the line 3—3 of Fig. 1 of one of the casings.

The improved device includes a central standard, preferably formed of a plurality of rods 10 grouped in parallel relation and 40 united by bolts 11 at suitable intervals. Each rod is bent laterally at the ends to form radiating arms 12, the lower arms forming feet to support the standard and its attachments.

45 Any required number of the rods may be employed but for the purpose of illustration four are shown.

The arms of each rod are in vertical alinement, and disposed between each alined pair 50 of arms is a casing, each formed with upper

horizontal members 13, lower horizontal members 14, and connecting vertical members 15.

The members 15 are connected at intervals by horizontal shelves 16 to form a series of 55 superimposed pockets between the vertical divisions 15 as shown. Extending across each pocket is a ledge or stop 17 to prevent the goods falling out.

The members 15 and 16 are arranged in 60 any desired manner to form pockets of any required size or outline, preferably as in Fig. 3 to receive articles of different sizes.

The improved device may be constructed of any required size and to form pockets of 65 any required dimensions or numbers for all the different forms of articles, but the improved device is particularly designed for holding bolts of varying sizes in convenient positions for use or display.

70 The standard members 10—12 will preferably be of rods of suitable size to withstand the strain to which they will be subjected, or they may be constructed of piping of any required dimensions. The receptacles or casings are supported for rotation on the members 12 by suitable pins represented at 18, so that the casing may be rotated to bring any of the pockets in convenient and accessible position.

75 The preferred embodiment of the invention is disclosed in the drawings and set forth in the specifications, but it will be understood that any modifications within the scope of the claim may be made in the 80 construction without departing from the principle of the invention or sacrificing any of its advantages.

85 Having thus described the invention what is claimed as new is:—

90 In a device of the class described, a non rotatable standard formed of a plurality of rods in parallel relation and fastened together and each having lateral extensions at the ends, and goods holding casings mounted 95 to rotate respectively between said extensions.

In testimony whereof, I affix my signature hereto.

CHARLES EDWARD KAYLOR.
